(57) **CLAIM**

The ornamental design for a portable heater as shown and described.

DESCRIPTION

FIG. 1 is a top front right perspective view of a portable heater showing my new design in a first position of use; FIG. 2 is a right side elevation view thereof shown in a first position of use, wherein the opposing side is a mirror image; FIG. 3 is a front elevation view thereof, shown in a first position of use; FIG. 4 is a rear elevation view thereof, shown in a first position of use; FIG. 5 is a top plan view thereof, shown in a first position of use; FIG. 6 is a bottom plan view thereof, shown in a first position of use; FIG. 7 is a top front right perspective view of the portable heater shown in FIG. 1 shown in a second position of use; and, FIG. 8 is a right side elevation view of the portable heater shown in FIG. 1, shown in a second position of use, wherein the opposing side is a mirror image. The broken lines in the Figures depict portions of the portable heater that form no part of the claimed design.
